JULIUS KINDERVATER, OF GREAT NECK, NEW YORK

STAYBOLT STRUCTURE

Application filed November 2, 1931. Serial No. 572,564.

This invention relates to flexible staybolt structures of the type comprising a sleeve adapted to be attached to a boiler shell, and formed with an internal spherical seat; a bolt member formed with an enlarged head adapted to fit within the sleeve and having a spherical face bearing on the seat; a cap at the end of the sleeve; and a diaphragm disposed on the sleeve around the head, providing a seal between the bolt and sleeve against the escape of steam.

The object of the present invention is to provide an improved staybolt structure of the type described, which will effect an efficient steam tight joint between the sleeve and the bolt member, and which will permit the widest possible range of turning movement of the bolt head, while imposing the slightest possible undesirable stresses on the diaphragm.

A further object is to provide a staybolt structure of the type described comprising an improved diaphragm which is characterized by greater flexibility and consequently will be of increased durability.

The invention is illustrated in the accompanying drawing, in which Figure 1 is a side view, in elevation, of a staybolt structure embodying the invention, applied to the shell sheet and fire box sheet of a boiler; Fig. 2 is a view, in central vertical section, on an enlarged scale, of the outer end of the staybolt structure shown in Fig. 1; Fig. 3 is a side view, in elevation, of the outer end of the staybolt; Fig. 4 is a plan view of the staybolt; Fig. 5 is a plan view of one-half of the sealing diaphragm; and Fig. 6 is a sectional view on the line VI—VI of Fig. 5.

In the practice of the invention, referring descriptively to the specific embodiment thereof which is herein exemplified, the staybolt structure comprises a bolt 1, having a threaded end portion 2, which is screwed into a threaded opening 3, in a fire box sheet 4. The inner end of the bolt is cut off after the bolt has been screwed into place, and the portion disposed on the inside of the fire box sheet is riveted, to provide a head 5, which locks the bolt to the fire box sheet.

The outer end of the bolt 1, is provided

with an enlarged head 6, comprising a spherical face 7, and extends through a sleeve 8, which is disposed in an opening 9, in the boiler shell 10. The sleeve 8 is secured in place in the usual manner by welding 11. The inner end of the sleeve 8 is inwardly curved, and the inside of the sleeve, at its inner end, is slightly, outwardly tapered at 12 to provide clearance between the sleeve and the bolt. The radius for the outer axially curved surface of the sleeve is struck from a center beyond the center line of the bolt. A spherical seat 13 is formed on the inner surface of the sleeve and the spherical face 7 of the bolt is adapted to engage the same and to have a relative ball and socket movement therewith. The seat is formed in the sleeve approximately mid-way of its length, and the sleeve engages the boiler sheet at its lower portion so that the head of the bolt is disposed outside of the boiler shell sheet.

To provide a seal between the bolt and the sleeve so as to prevent the escape of steam, a circular sealing diaphragm 14 is provided. The upper end of the head 6 of the bolt is provided with a reduced threaded extension 15, and an annular clamping face 16 is formed cross-axially of the bolt at the inner end of the reduced extension 15. The diaphragm 14 is provided with a central opening 17, through which the extension 15 passes, the diaphragm, around the periphery of its opening, resting upon the clamping face 16. A washer 18 is disposed over the diaphragm and a nut 19 is screwed on the extension 15 over the washer, thus clamping the inner portion of the diaphragm securely to the face 16.

The diaphragm 14 comprises a laminated structure formed of a plurality of layers 14a, 14b and 14c (Fig. 6), suitably pressed together, and to provide free movement of the diaphragm so as to permit the headed portion of the bolt to assume a wide range of turning movement on the seat of the sleeve without imposing shearing stresses on the diaphragm, a corrugation 20 is formed near the outer periphery of the diaphragm, concentric with the axis thereof. The outer

rim of the diaphragm is clamped to the top of the sleeve 8 by a cap 21, which is provided with an inner screw-threaded face 22, which engages threads 23 formed on the exterior of the upper end of the sleeve 8. The cap is provided with an opening 24 in its top leaving the nut and part of the washer exposed. The head 6 of the bolt is slotted at 25 so as to permit a tool to be inserted to turn the bolt for the purpose of inserting or removing the same. A telltale hole 26 is formed centrally in the bolt throughout the entire length.

Of the essence of the present invention are the relative proportions and positions of the head of the bolt, its spherical face, and the diaphragm. The spherical face 7 on the head of the bolt is struck from a radius greater than the diameter of the bolt and having its center point 27, on the center line of the bolt, and the seat 13 is of a conforming spherical shape, as indicated by the arc 28. The diaphragm 14 is substantially in the same plane as the said center point. It will thus be apparent that by virtue of these positions and proportions, when the bolt moves relatively to the sleeve and the spherical face 7 slides upon the seat 13, the movement of the diaphragm will be substantially inappreciable, as distinguished from the relatively large amount of movement which would exist if the diaphragm was not in substantially the same plane as the center from which the spherical face is struck. By this construction a minimum amount of movement is required of the diaphragm, so that a diaphragm of relatively small diameter may be employed, and in operation, the life of the same, because of the small amount of movement required, will be increased to a maximum duration. By providing spherical surfaces for the face 7 of the bolt and the seat 13 of the sleeve instead of straight tapered surfaces, seizing, gripping, and wedging are avoided.

While there has been hereinbefore described an approved embodiment of the instant invention, it will be understood that many and various changes and modifications may be made thereto, without departing from the spirit of the instant invention, and that all and any such changes and modifications as fall within the scope of the appended claim are contemplated as a part of the instant invention.

The invention claimed and desired to be secured by Letters Patent is:

A flexible staybolt structure comprising a sleeve adapted to be secured in an opening in a boiler sheet and having an inner seat; an annular transverse diaphragm associated with said sleeve; a bolt having a passageway extending longitudinally therethrough from end to end, and a head disposed within said sleeve, provided with a spherical face adapt-

ed for universal movement on said seat and for movement outwardly from said seat, said face being struck from a center point on the axis of the bolt, said head having a reduced portion outwardly beyond said face providing a space laterally therebeyond within said sleeve, said annular transverse diaphragm being located approximately at said center point and secured at its outer periphery to said sleeve and at its inner periphery to said head at said reduced portion, and having a bend permitting said movements of the bolt; and a backing member adjacent the outer face of the diaphragm secured to the bolt and extending across said space for supporting the diaphragm against boiler pressure.
